UNITED STATES PATENT OFFICE.

FRANK A. EDWARDS, OF CHICAGO, ILLINOIS, ASSIGNOR OF ONE-HALF TO ARTHUR SPARROW, OF CHICAGO, ILLINOIS.

BARBER'S AND HAIR-DRESSER'S SHAMPOO AND HAIR-WASHING DEVICE.

1,360,382.

Specification of Letters Patent. Patented Nov. 30, 1920.

Application filed March 19, 1920. Serial No. 367,165.

To all whom it may concern:

Be it known that I, FRANK A. EDWARDS, a citizen of the United States, and a resident of the city of Chicago, in the county of Cook 5 and the State of Illinois, have invented certain new and useful Improvements in Barbers' and Hair-Dressers' Shampoo and Hair-Washing Devices, of which the following is a specification, reference being had to the 10 accompanying drawings, forming a part thereof.

The purpose of this invention is to provide an improved device especially adapted for the use of barbers and hairdressers. It 15 consists in the elements and features of construction shown and described as indicated in the claims.

In the drawings:

Figure 1 is a plan view of a water fixture 20 of the nature of a hand basin equipped with the device embodying this invention.

Fig. 2 is a section at the line, 2—2, on Fig. 1.

Fig. 3 is a section at the line, 3—3, on 25 Fig. 2.

Fig. 4 is a section at the line, 4—4 on Fig. 1.

Fig. 5 is a section at the line, 5—5, on Fig. 3, showing the terminal quadrant pipe arm 30 which carries the spray head turned to oblique position, as in dotted line in said Fig. 3.

Fig. 6 is an elevation of the upper portion of the telescopic standard of the device 35 and its terminal parts adjusted to position for use.

The device shown in the drawings is designed especially for shampooing and hair washing in barber shops and ladies' "beauty parlors" respectively, taking the place of the 40 considerably inconvenient appliances now employed; which in the least inconvenient form consists usually of the spray device carried at the end of a flexible tube which at 45 the other end is adapted to be coupled onto an erect discharge nozzle, with which the stand having the hand bowl is equipped in such position that the head of the customer being served, may be held over the bowl while the 50 operator directs the spray terminal over the customer's head during massaging of the scalp which has been preparatorily annointed with a lather producing substance. In this commonly employed method, the operator at 55 all times has one hand occupied in holding

and directing the spray nozzle, and can use only one hand for massaging and otherwise manipulating the scalp or hair of the customer; and beside the embarrassment of having only one hand free for his work, the 60 flexible tube connection of the spray head having a tendency to lop to one side or the other, interferes to some extent with the easy direction of the spray to the proper point. 65

Avoiding these deficiencies of the present devices, the structure shown in the drawings comprises in its main elements, first, a telescopically - extensible standard member adapted to be applied by direct thrust to 70 and held firmly upon the erect nozzle of the stand; second, a horizontally-extending pipe member carried by the inner pipe member of the telescoping standard and swiveled about its own axis at its connection with 75 said pipe member which in turn swivels about its axis in the standard; third, a quadrant pipe arm swiveled transversely to the horizontally-extending arm at the outer end, and adapted at its free end for carrying a spray head or other nozzle terminal. 80

The standard member is adapted to be applied directly to the up-standing discharge nozzle of the stand. The pipe is provided with a considerably thick elastically - compressible—and thereby radially - shrinkable—gasket, preferably of rubber, and means on the standard for compressing it to grip the standard onto the stand strongly enough to support the entire fixture almost 90 as rigidly as it might be supported by a threaded metallic coupling. The extensibility of the telescoping standard adapts it to be adjusted to the convenience of the customer and the operator, and the detail construction of this standard is such as to prevent it from being extended by the water pressure. The three swiveled connections in the fitting between the standard and the quadrant terminal pipe having the spray 100 head, makes the spray head substantially as free to be moved around the head of the customer by the operator and turned to discharge in any direction, as if it were connected by a perfectly flexible pipe throughout; and at the same time the connections at these several swivel joints are such as to make the swiveled members thereat tight enough so that the fixture will hold its position against gravity and against the tend- 105 110

ency of the water pressure to deflect it; so that the operator may adjust the spray nozzle at any desired position over the head of the operator while both his hands are left 5 free to massage the customer's scalp or manipulate the hair with comb or brush, or otherwise by hand, as the operation being performed may require.

The detail construction will now be described. A is the stand containing the hand bowl or basin B, provided with hot and cold water pipes controlled by the valves, C and D, and both connected to the standard discharge nozzle, E. The outer pipe member, 1, of the standard is expanded at its lower end as seen at 1^a, and interiorly threaded, and exteriorly provided with hexagon wrench engagement, 1^b, and back of the interior thread, it has an annular diaphragm, 1^c, forming an annular shoulder, 1^d facing downward, on which there is preferably lodged a washer, 2, for intervening between said shoulders and the elastically-compressible and radially-shrinkable rubber packing 25 gasket, 5, whose depth in axial direction is very considerable for the purpose of affording capacity for compression to result in the radial shrinkage by which it may grasp tightly the stand nozzle, E. 4 is an exteriorly-threaded hollow plug or bushing, interiorly counterbored to receive the packing gasket, 5, and exteriorly threaded for engaging the interior thread of the standard terminal, 1^a, of the pipe member, 1, so that 30 upon being screwed into the expanded end, 1^a, of the exterior pipe member, 1, said plug serves to axially compress and radially shrink the gasket, 5, to cause it to grip tightly the nozzle, E. At the upper side the 35 diaphragm, 1^c, is counterbored to form a second upwardly-facing shoulder, 1^e, upon which is seated the lower end of the intermediate pipe member, 2. Said pipe member, 2, has above and back of its said lower 40 end a diaphragm, 2^a, blocking off its interior cavity, and immediately below said diaphragm a multiplicity of radial apertures, 2^b, by which communication is afforded with the interspace, 2^d, between the outer 45 pipe member, 1, and the intermediate pipe member, 2. Said interspace extends substantially the entire interlapped length of said members, 1 and 2, the interior member, 2, being seated at its upper end on an interiorly-projecting boss, 1^h, of the pipe, 1, which forms a shoulder blocking the upper 50 end of said interspace, 2^d. From said interspace, 2^d, there is communication through the apertures, 2^b, formed near the upper end 55 of said member, 2, immediately below the interior boss and shoulder, 1^h, said apertures leading into the interspace, 3^d, between said intermediate pipe member, 2, and the central pipe member, 3. Said interspace, 3^d, is 60 blocked at the upper end by a washer, 6, 65

fitted within the reduced upper end of the exterior member, 1, and lodged upon the upper end of the intermediate member, 2, and fitting closely around the central member, 3. The interspace, 3^d, communicates at 70 its lower end with the central bore of the central member, 3, through apertures, 3^b, in the fitting, 3^a, by which the central member, 3, is terminated at its lower end, said fitting having an exterior annular boss, 3^c, which 75 fits saugly piston-wise in the bore of the intermediate member, 2, and thereby blocks off the interspace, 3^d, at the lower end, compelling the communication between said interspace and the central bore of the interior member, 2, to be through said apertures, 3^b. The fitting, 3^a, is open at its lower end, effecting communication with the cavity 2^b, produced between the bottomed lower 80 end of the intermediate member, 2, and said 85 blocking boss, 3^c, for the purpose and with the effect hereinafter referred to. The communication through the central bore of the central member, 3, is unobstructed throughout the remainder of the device. 90

The operation of the structure of the telescoping standard as described is that the pressure admitted through the apertures, 3^b, into the space, 2^b, acts for upward thrust of said member over the annular area equal 95 to the interior diameter of the intermediate element to less the interior diameter of the inner pipe member, 3; and the pressure admitted through the apertures, 2^c, acts in the opposite direction over the annular area of 100 the interior diameter of the pipe member, 2, less the exterior diameter of the central member, 3. The difference between the two pressures, being the net pressure operating for upward thrust of the central member, 105 3, is measured by the annular cross-sectional area of the walls of the central member, 3; and this upward-acting pressure is resisted by the total friction of the parts sliding upon each other; which is adequate, and 110 more than adequate at all ordinary water-supply pressures, to withstand said net upward pressure; so that there is no liability to upward thrust or extension of a telescoping structure resulting from the water pressure, while at the same time the user can 115 readily extend or reduce the extension of said telescoping structure.

10 is an angle fitting rigidly secured at the upper end of the central pipe member, 120 3, on the standard. The limb, 10^a, of said angle fitting is exteriorly threaded and interiorly bored and counterbored to form a shoulder, 10^b, on which the end of the horizontal pipe member, 12, is stopped and 125 seated for making a substantially liquid-tight joint, provided said end is held against said seat. For so holding it there is secured onto the end of said pipe member, 12, which is inserted in the bored and counterbored 130

limb, 10^a, a rigid collar, 12^a, of such length that its outer end is a little beyond the outer end of the threaded limb, 10^a, of the angle fitting, so that the packing, 11^a, which is 5 provided in the cavity of the stuffing box coupling member, 11, screwed onto the threaded limb, 10^a, of the angle fitting, engages said outer end of the collar,—said end constituting a shoulder,—for crowding the 10 horizontal pipe member, 12, into the fitting to seat either the end of the pipe on the shoulder, 10^a, or the inner end of the collar, 12^a, on the shoulder, 10^a, which results from counter-boring the rigid limb, 10^a, to 15 admit the collar, 12^a. By this means there is formed a securely liquid-tight joint which permits the swiveling action of the horizontal pipe member, 12, with respect to the angle fitting, 10. At the opposite or 20 free end of the pipe member, 12, it has secured to it the angle pipe fitting, 13, having the exteriorly threaded and interiorly counterbored limb 13^a, similarly substantially to the fitting, 10, for the purpose of 25 connecting with said fitting, 13, a quadrant pipe member in substantially the same manner and with substantially the same capacity for swiveling, as described with respect to the connection of a pipe member, 30 12, with the fitting, 10. For the purpose of the joint at this point the stuffing box coupling member, 14, is knurled at 14^a, for manipulation by hand, whereas the stuffing box coupling member, 11, is preferably 35 formed for wrench engagement at the corresponding place, because it is desirable to have the joint at the fitting, 10, with the fitting, 12, tighter and less easy as to the swiveling action of the pipe, 12, therewith, 40 than is desirable with respect to the connection of the quadrant pipe member, 15, with the fitting, 13. The free end of the quadrant pipe member, 15, is adapted to receive any desired form of discharge nozzle, and for the specific purpose of the device, namely for shampooing, hair washing, 45 and the like, is a spray head, 16. It will be understood that the provision of the three swivel joints, namely, of the pipe member, 3, with respect to the remainder of the telescoping standard, of the pipe member, 12, with respect to the angle fitting, 10, and of the quadrant member, 15, with respect to the angle fitting, 13, in view of the 50 90-degree turn of said quadrant pipe between its swivel connection and the spray head at the opposite ends, tend to adapt the device for use in the manner described in its manipulation in the process of shampooing or like operation.

By substituting a bubbling cup, 18, in Fig. 6 for the spray device, and turning the part to the position shown in said Fig. 6 so that the quadrant pipe member when turned 55 upward presents a bubbling cup at the up-

per end, the device may be readily converted into a drinking fountain, the bubbling cup being swung over to position overhanging the hand bowl while the user manipulates the cold water faucet until the fixture is cool 70 and the water so discharged at a suitable temperature for drinking, and then reversing the position to that shown in Fig. 6 for use as a bubbling cup from which the excess of water flows over into the bowl. 75

I claim:—

1. In a device for the purpose indicated, a telescoping structure comprising an odd-numbered plurality of tubes, forming a like number of concentric passages, each intermediate or even-numbered passage having communication at its opposite ends respectively with the next interior and exterior passages, and being stopped off or blocked as to fluid flow beyond said communications 80 respectively, each odd-numbered passage being also stopped off or blocked as to fluid flow beyond its communication with the next interior even-numbered passage. 85

2. In the construction defined in claim 1 90 foregoing, the blocking means of the outermost passage and of the next to the innermost passage at the outer and inner ends of said passages respectively, being rigid respectively with the outermost and innermost 95 of said tubes; whereby the discharge pressure tends to cause telescopic retraction of said innermost tube with respect to the outermost.

3. In the construction defined in claim 1 100 foregoing, the number of pipes being three and the intermediate pipe being fixed with respect to the outermost, the blocking means of the intermediate passage beyond its communication with the central passage being rigid with the central tube, and the other blocking means of said intermediate passage being stopped with respect to the outermost tube and free with respect to the innermost. 105

4. In the construction defined in claim 1 110 foregoing, the number of tubes and concentric passages being three, the outer tube having an annular diaphragm restricting its inlet opening, the middle tube having its inner 115 end closed and extended beyond said closure for stopping on said annular diaphragm, the said extension being apertured for liquid flow from the inlet tube into the outer of the three concentric passages. 120

5. In the construction defined in claim 1 125 foregoing, means for attaching the device to a discharge pipe, consisting of a plug or bushing centrally apertured and counterbored and exteriorly threaded for screwing into the inlet end of the outer of said concentric tubes, and a compressible and contractile elastic packing sleeve occupying the counterbore of said nut, and stopped at one end on the counter-bore shoulder, said 130

- outermost tube having at its inlet end an annular diaphragm restricting its aperture, and stopping the opposite end of said compressible and contractible packing.
- 5 6. In a device of the character indicated, an inner tube member, a second tube member within which the first mentioned is telescopically mounted, the outer of the two tube members having one end closed, the 10 inner one having at that end an exterior flange which fits piston-wise in the outer of said tubes and having apertures beyond said flange in the discharge direction away from said flange, the outer tube having liquid inlet 15 apertures back of said blocking member, and an inclosing tube through which liquid under pressure may be admitted through both said apertures for discharge through the inner tube; whereby the pressure operating 20 between the flange and the annular blocking member, tending to resist telescopic extension of the device, is opposed by pressure at the opposite side of said flange between the same and the closed ends of the outer of said 25 two tubes.
7. A device for the purpose indicated, comprising a plural-tubed telescopic upright member having near the lower end of the outer tube an interior annular shoulder; an 30 elastically compressible and thereby radially-shrinkable packing ring lodged within said lower end and seating on said shoulder and protruding from said end and a centrally-apertured and counterbored plug or bushing screwed into said lower end of said tube.
8. A device for the purpose indicated, comprising an up-standing telescopically-extensible member adapted for securement of its lower end onto a discharge pipe; a horizontally-extending pipe arm swiveled about its horizontal axis to the upper end of the interiorly-telescoping member of the standard, and a substantially quadrant-band pipe arm swiveled transversely to the outer end 40 of said horizontal pipe arm, and having its own outer end adapted to receive a terminal discharge device.
9. In the construction defined in claim 8 foregoing, a stuffing box at the upper end 50 of the outer pipe member of the telescoping standard for closing the joint between the same and the inner telescoping member thereof, said stuffing box having an upward exteriorly-threaded extension above its wrench engagement, said extension being longitudinally slit to form fingers adapted to be closed together to grip the interior telescoping tube member, and a nut screwed onto said threaded and slit extension for 60 clamping fingers onto the interior telescoping member for frictional resistance to its turning about its axis in the standard.
- In testimony whereof I have hereunto set my hand at Chicago, Illinois, this 15th day 65 of March, 1920.

FRANK A. EDWARDS.
